FIG. 4

REKEYABLE LOCK CYLINDER WITH ENHANCED TORQUE RESISTANCE

RELATED APPLICATIONS

This application is a continuation of U.S. patent application Ser. No. 16/825,817, now U.S. Pat. No. 11,988,018, filed Mar. 20, 2020, which is a continuation of U.S. patent application Ser. No. 15/172,206, now U.S. Pat. No. 10,612,271, filed Jun. 3, 2016, which claims the benefit of U.S. Provisional Application No. 62/180,339, filed Jun. 16, 2015, and which applications are hereby incorporated by reference in their entirities.

TECHNICAL FIELD

This disclosure relates generally to locks; in particular, this disclosure relates to a lock with a rekeyable lock cylinder having enhanced torque resistance.

BACKGROUND AND SUMMARY

Lock cylinders that can be rekeyed without removal of the cylinder plug are known. For example, U.S. Pat. No. 8,033,150 describes a rekeyable lock cylinder. These types of locks are highly beneficial to consumers because the locks can be easily rekeyed without use of a locksmith.

Although the plug cylinder should freely rotate when an authorized key is inserted into the keyway, the lock cylinder should be configured to resist rotation of the plug when torque is applied by an unauthorized key (or other object). A high amount of torque resistance for the lock cylinder is key to reducing forced entry. Therefore, there is a need for a rekeyable lock with enhanced torque resistance.

According to one aspect, this disclosure provides a rekeyable lock cylinder with a cylinder body and a plug assembly. The cylinder body defines a longitudinal axis and includes a groove. The plug assembly is disposed in the cylinder body and is rotatable about the longitudinal axis. The lock cylinder includes a plurality of key followers and a corresponding plurality of racks disposed in the plug assembly. At least one of the plurality of racks is selectively disengageable from at least one of the plurality of key followers responsive to application of a force by an object inserted into the rekeyable lock cylinder to facilitate rekeying to a new key. The lock cylinder includes means for blocking rotation of the plug assembly with respect to the cylinder body to prevent unlocking of the rekeyable lock cylinder with an unauthorized object. In some embodiments, the blocking means is configured such that torqueing the plug assembly with an unauthorized object applies force to the blocking means without translating such force to the plurality of racks. This type of arrangement enhances torque resistance of the lock cylinder.

In some embodiments, the blocking means includes a locking bar movable transversely with respect to the longitudinal axis between a locked position into the groove of the cylinder body and an unlocked position out of the groove of the cylinder body. For example, the locking bar could include a surface that engages a surface of the groove when in the locked position. In some illustrative embodiments, the respective surfaces of the locking bar and groove that engage when the locking bar is in the locked position are in approximately parallel planes. Depending on the circumstances, the surface of the locking bar that engages the groove in the cylinder body when the locking bar is in the locked position is not a ramped surface. For example, the

surfaces could be flat with respect to each other. In some cases, the edge of the locking bar is substantially squared off, such as having an approximately rectangular cross-section.

In some embodiments, there are one or more biasing members urging the locking bar towards the plurality of racks. With this arrangement, the biasing members urge the locking bar out of the groove in the cylinder body when an authorized key is inserted into the keyway. In some illustrative embodiments, a spring force of the biasing member is less than a spring force of the spring-loaded key followers. As such, the spring-loaded key followers will overcome the spring force of the biasing member to lock the lock cylinder when a key is not inserted into the keyway.

Additional features and advantages of the disclosure will become apparent to those skilled in the art upon consideration of the following detailed descriptions exemplifying the best mode of carrying out the disclosure as presently perceived.

BRIEF DESCRIPTION OF THE DRAWINGS

The present disclosure will be described hereafter with reference to the attached drawings which are given as non-limiting examples only, in which:

FIG. 1 is a perspective view of an example lock cylinder according to an embodiment of this disclosure;

FIG. 2 is an exploded view of the example lock cylinder shown in FIG. 1;

FIG. 3 is a cross-sectional view of the example lock cylinder shown in FIG. 1 showing the springs urging the locking bar towards the racks;

FIG. 4 is a cross-sectional view of the example lock cylinder shown in FIG. 1 showing the interface between the locking bar and cylinder body with an authorized key in the keyway;

FIG. 5 is a cross-sectional view of the example lock cylinder shown in FIG. 1 showing the interface between the locking bar and cylinder body with an unauthorized key in the keyway; and

FIG. 6 is a cross-sectional view of the example lock cylinder shown in FIG. 1 showing the interface between the locking bar and cylinder body without a key in the keyway.

Corresponding reference characters indicate corresponding parts throughout the several views. The exemplification set out herein illustrates an embodiment of the invention in one form, and such exemplification is not to be construed as limiting the scope of the invention in any manner.

DETAILED DESCRIPTION

This disclosure relates to a rekeyable lock cylinder that can be rekeyed without removal of the cylinder plug. The operation for rekeying the lock cylinder is similar to that described in U.S. Pat. No. 8,033,150, which is hereby incorporated by reference. While the rekeying operation operates similarly, the present lock cylinder includes an enhanced torque resistance. In some embodiments, this enhanced torque resistance is configured in a manner that isolates torque on the plug cylinder from the racks, which increases durability of the lock cylinder.

An illustrative lock cylinder 10, according to an embodiment of the present disclosure, is illustrated in FIGS. 1 and 2. The lock cylinder 10 includes a longitudinal axis 12, a cylinder body 14, and a plug assembly 16. A retainer clip 18 (FIG. 2) couples together the cylinder body 14 with the plug assembly 16.

The cylinder body 14, as best seen in FIG. 2, illustratively includes a generally cylindrical body 20 having a front end 22, a back end 24 and a cylinder wall 26 defining an interior surface 28. The cylinder wall 26 includes an interior, locking bar-engaging groove 30 (best seen in FIGS. 4, 5, 6). In some embodiments, the locking bar-engaging groove 30 has a generally rectangular-shaped cross-section and extends longitudinally along a portion of the cylinder body 14, typically from the front end 22.

The plug assembly 16 includes a plug body 32, a carrier subassembly 34 and a plurality of spring-loaded pins 38 (also called key followers). The plug body 32 illustratively includes a plug face 36, an intermediate portion 40 and a drive portion 42. The plug face 36 defines a keyway opening 44, a rekeying tool opening 46, and a pair of channels 48 extending radially outwardly for receiving anti-drilling ball bearings 50. The drive portion 42 is configured to drive a torque blade 51, which could be coupled with a latch assembly (not shown). The drive portion 42 further includes a pair of slots 52 formed in its perimeter and a central groove 54 for receiving the retainer clip 18 to retain the plug body 32 in the cylinder body 14.

The intermediate portion 40 includes a main portion 56 formed as a cylinder section and having a plurality of channels 58 for receiving the spring-loaded pins 38. The channels 58 illustratively extend transversely to the longitudinal axis of the plug body 32.

A planar surface 60 defines a recess 62 for receiving a retaining cap 64. The channels 58 extend partially through the plug body 32, with the sidewalls of the channels open to a planar surface 66. The planar surface 66 illustratively includes a plurality of bullet-shaped, rack-engaging features 68.

The carrier subassembly 34 includes a carrier 70, a plurality of racks 72, a spring catch 73, a locking bar 74, a pair of clips 76 for holding corresponding biasing members 78 against the locking bar 74 to urge the locking bar 74 against the racks 72, and a return spring 80. The carrier 70 includes a body 82 in the form of a cylinder section that is complementary to the main portion 56 of the plug body 32, such that the carrier 70 and the main portion 56 combine to form a cylinder that fits inside the cylinder body 14. The carrier 70 includes a curved surface 84 and a flat surface 86. The curved surface 84 includes a locking bar slot 88, a spring catch recess 90, and a pair of clip receiving recesses 100 for receiving the clips 76. The locking bar slot 88 illustratively includes a pair of biasing member-receiving bores 92 for receiving the biasing members 78. In the embodiment shown, the locking bar 74 includes a corresponding pair of recessed areas 96 for receiving the biasing members 78.

The spring-loaded locking bar 74 is sized and configured to fit in the locking bar slot 88 in the carrier 70. The locking bar 74 illustratively includes a blocking portion 98 that is received in the locking bar engaging groove 30 in the cylinder body 14 when in the locked position (FIGS. 5 and 6) and extends out of the locking bar engaging groove 30 when in an unlocked position (FIG. 4). In some embodiments, as illustratively shown, the blocking portion 98 has a squared-off edge that forms a rectangular cross-section.

This squared-off surface stands in contrast to the triangular-shaped edge of the locking bar described in U.S. Pat. No. 8,033,150, which moves out of the groove in the cylinder body via a camming action. By using the urging of biasing members 78 to move the blocking portion 98 out of the groove 30 in the cylinder body 14, a squared-off edge can be used with a corresponding flat surface in the locking bar

engaging groove 30, thereby increasing torque resistance of the lock cylinder 10 compared to the triangular-shaped edge and corresponding triangular-shaped locking bar engaging groove described in U.S. Pat. No. 8,033,150. Moreover, this

5 relieves stress on the racks 72 because torque applied by an unauthorized key (or other object) will not be translated from the locking bar 74 to the racks 72 via a camming action; instead, the locking bar 74 interface with the locking bar engaging groove 30 will isolate the torque from the racks

10 72. Opposite the squared-off edge of the blocking portion 98, the locking bar 74 includes a flange 102 configured to engage locking bar-engaging grooves 104 formed in the racks 72 (FIGS. 4, 5, 6). The flat surface 86 of the carrier 70 includes a plurality of parallel rack-receiving slots 94 15 extending perpendicular to the longitudinal axis of the carrier 70.

FIG. 3 is an illustrative cross-sectional view of the lock cylinder 10 transversely cut through one of the clips 76. In this view, it can be seen that the clips 76 extend around the 20 carrier 70. One end of the biasing member 78 is fixed against a receiving portion 106 of the clip 76 and the other end is received in the recessed area 96 of the locking bar 74 and urges the locking bar 74 against the racks 72. In this embodiment, the locking bar 74 is continuously urged by the 25 biasing members 78 against the racks 72.

FIGS. 4, 5, and 6 are illustrative cross-sectional views of the lock cylinder 10 transversely cut along the blocking portion 98 of the locking bar 74. In FIG. 4, which shows an authorized key 108 inserted into the keyway opening 44, the 30 key cut of the authorized key 108 is such to move the spring-loaded pins 38 and thereby the racks 72 to a position in which the flange 102 of the locking bar 74 is received into the respective locking bar engaging grooves 104 of the racks 72 via the urging of the biasing members 78. This positions

35 the blocking portion 98 of the locking bar 74 to its unlocking position out of the locking bar engaging groove 30, thereby allowing free rotation of the plug assembly 16 with respect to the cylinder body 14 to unlock the lock cylinder 10. This use of biasing members 78 to urge locking bar 74 out of the 40 locking bar engaging groove 30 stands in contrast to the camming action to move locking bar out of a groove in the cylinder body described in U.S. Pat. No. 8,033,150. FIG. 5 illustrates an example in which an unauthorized key 110 is inserted into the keyway opening 44. Since the key cut of the 45 unauthorized key 110 is "unauthorized," the locking bar engaging groove 104 of at least one of the racks 72 is not aligned with the flange 102 of the locking bar 74. As such, the locking bar 104 cannot be urged out of the locking bar engaging groove 30 of the cylinder body 14, which means the blocking portion 98 prevents rotation of the plug assembly 16 with respect to the cylinder body 14. In the embodiment shown, the edge of the blocking portion 98 is squared-off and the locking bar engaging groove 30 of the cylinder body 14 has a corresponding shape. This means that the

50 force caused by torquing the plug assembly 16 with respect to the cylinder body 14 will be applied to a flat surface 112 of the blocking portion 98 with respect to a flat interior surface 114 of the locking bar engaging groove 30. Since the surfaces 112, 114 are flat with respect to each other, this

55 enhances torque resistance compared to a ramped surface, such as the triangular edge of the locking bar and corresponding triangular groove in the cylinder body of U.S. Pat. No. 8,033,150. Moreover, unlike the flat surfaces 112, 114, the ramped surfaces described in U.S. Pat. No. 8,033,150 creates a camming action that applies force to the racks, which in some cases can deform the racks, or otherwise 60 reduce durability of the racks. FIG. 6 illustrates an example

in which there is no key in the lock cylinder 10. The springs of the spring-loaded pins 38 have a higher spring force than the biasing members 78. Accordingly, without a key in the keyway, the spring-loaded pins 38 drive the racks 72 downward, overcoming the force of biasing members 78, so that the flange 102 of the locking bar 74 is not received in the locking bar engaging grooves 104 of the racks 74. This forces the blocking portion 98 of the locking bar 74 into the locking bar engaging groove 30 of the cylinder body 14, which prevents rotation of the plug assembly 16 with respect to the cylinder body 14.

EXAMPLES

Illustrative examples of the rekeyable lock cylinder disclosed herein are provided below. An embodiment of the rekeyable lock cylinder may include any one or more, and any combination of, the examples described below.

Example 1 is a rekeyable lock cylinder with a cylinder body having a longitudinal axis and including a groove. The lock cylinder includes a plug assembly disposed in the cylinder body that is rotatable about the longitudinal axis. A plurality of key followers with a corresponding plurality of racks are disposed in the plug assembly. At least one of the plurality of racks is selectively disengageable from at least one of the plurality of key followers responsive to application of a force by an object inserted into the rekeyable lock cylinder to facilitate rekeying to a new key. The lock cylinder includes means for blocking rotation of the plug assembly with respect to the cylinder body to prevent unlocking of the rekeyable lock cylinder with an unauthorized object. The blocking means is configured such that force from torquing the plug assembly with an unauthorized object is primarily distributed between the cylinder body and blocking means compared with any force translated to the plurality of racks, thereby enhancing torque resistance of the rekeyable lock cylinder.

In Example 2, the subject matter of Example 1 is further configured such that the blocking means comprises at least one locking bar movable transversely with respect to the longitudinal axis between a locked position into the groove of the cylinder body and an unlocked position out of the groove of the cylinder body.

In Example 3, the subject matter of Example 2 is further configured such that the at least one locking bar includes a surface that engages a surface of the groove when in the locked position. The respective surfaces of the at least one locking bar and groove engage when the at least one locking bar is in the locked position are in approximately parallel planes.

In Example 4, the subject matter of Example 3 is further configured such that the surface of the at least one locking bar that engages the groove in the cylinder body when the at least one locking bar is in the locked position is not a ramped surface.

In Example 5, the subject matter of Example 3 is further configured such that the surface of the at least one locking bar that engages the groove in the cylinder body when the at least one locking bar is in the locked position is a flat surface.

In Example 6, the subject matter of Example 3 is further configured such that the surface of the at least one locking bar that engages the groove in the cylinder body is in a plane that is approximately parallel to an axis radial to the longitudinal axis.

In Example 7, the subject matter of Example 2 is further configured such that an edge of the at least one locking bar is received in the groove of the cylinder body when in the locked position.

5 In Example 8, the subject matter of Example 7 is further configured such that the edge of the at least one locking bar is substantially squared off.

10 In Example 9, the subject matter of Example 7 is further configured such that the edge of the at least one locking bar has an approximately rectangular cross-section.

15 In Example 10, the subject matter of Example 1 is further configured to include a biasing member urging the blocking means towards the plurality of racks.

20 In Example 11, the subject matter of Example 10 is further configured such that the plurality of key followers are spring-loaded and wherein a spring force of the biasing member is proportional to a spring force of the spring-loaded key followers to ensure any key follower will not be lifted by the at least one locking bar.

25 Example 12 is a rekeyable lock cylinder including a cylinder body with a longitudinal axis including a groove. The lock cylinder includes a plug assembly disposed in the cylinder body and being rotatable about the longitudinal axis.

30 A carrier assembly is provided that includes a plurality of racks and at least one locking bar. The lock cylinder includes a plurality of key followers disposed in the plug assembly. At least one of the plurality of racks is selectively disengageable from at least one of the plurality of key

35 followers responsive to application of a force by an object inserted into the rekeyable lock cylinder to facilitate rekeying to a new key. The at least one locking bar is movable transverse to, and rotationally about the longitudinal axis. At least a portion of the at least one locking bar is movable

40 between a locked position in the groove of the cylinder body and an unlocked position out of the groove in the cylinder body. The at least one locking bar is configured to prevent unlocking of the rekeyable lock cylinder with an unauthorized object. The at least one locking bar is configured such

45 that force from torquing the plug assembly with an unauthorized object is primarily distributed between the cylinder body and carrier assembly compared to any force translated to the plurality of racks.

50 In Example 13, the subject matter of Example 12 is further configured such that a biasing member urges the at least one locking bar towards the plurality of racks.

In Example 14, the subject matter of Example 12 is further configured such that the plurality of key followers are spring-loaded and a spring force of the biasing member is less than a spring force of the spring-loaded key followers.

55 Example 15 is a rekeyable lock cylinder that includes a cylinder body with a longitudinal axis including a groove. A plug assembly is disposed in the cylinder body and is rotatable about the longitudinal axis. The lock cylinder includes a plurality of key followers and a corresponding plurality of racks disposed in the plug assembly. At least one of the plurality of racks is selectively disengageable from at least one of the plurality of key followers responsive to application of a force by an object inserted into the rekeyable lock cylinder to facilitate rekeying to a new key. At least one locking bar is movable transverse to, and rotationally about the longitudinal axis. At least a portion of the at least one locking bar is movable between a locked position in the groove of the cylinder body and an unlocked position out of the groove in the cylinder body. The portion of the at least one locking bar is received into the groove has an approximately rectangular cross-section. The lock cylinder includes

60

65

a biasing member that urges the at least one locking bar towards the plurality of racks.

In Example 16, the subject matter of Example 15 is further configured such that the plurality of key followers are spring-loaded and a spring force of the biasing member is less than a spring force of the spring-loaded key followers.

Although the present disclosure has been described with reference to particular means, materials, and embodiments, from the foregoing description, one skilled in the art can easily ascertain the essential characteristics of the invention and various changes and modifications may be made to adapt the various uses and characteristics without departing from the spirit and scope of the invention.

What is claimed is:

1. A rekeyable lock cylinder comprising:
a cylinder body extending along a longitudinal axis, the cylinder body defining an interior surface having a first engaging groove extending along the longitudinal axis; and
a plug assembly at least partially disposed within the cylinder body and selectively rotatable around the longitudinal axis, the plug assembly comprising:
a plug body;
a plurality of key followers slidably mounted on the plug body; and
a carrier subassembly supported on the plug body, the carrier subassembly comprising:
a carrier slidably supported on the plug body;
a plurality of racks slidably mounted on the carrier, each of the plurality of racks engaged with a corresponding key follower of the plurality of key followers, wherein the plurality of racks are selectively disengageable from the plurality of key followers via movement of the carrier to facilitate rekeying of the lock cylinder, each of the plurality of racks having a second engaging groove recessed within a first side of the rack, wherein the second engaging groove has an opening distance at the first side; and
a locking bar supported on the carrier and having a blocking portion configured to be received at least partially within the first engaging groove of the cylinder body and an opposite flange configured to be received at least partially within the second engaging groove of the plurality of racks, the locking bar movable between at least a locked position engaged with the first engaging groove of the cylinder body for blocking rotation of the plug assembly, and an unlocked position disengaged from the first engaging groove of the cylinder body allowing rotation of the plug assembly, the locking bar biased towards the plurality of racks with one or more biasing members, wherein the locking bar includes a first surface and a second surface, the first and second surfaces parallel to each other and extending between the blocking portion and the flange, the locking bar having a thickness distance between the first and second surfaces that is less than the opening distance of the second engaging groove, and wherein when the locking bar is in the unlocked position, the flange is fully received within the second engaging groove such that gaps are formed between the first side of the rack and the first and second surfaces of the locking bar along a plane defined by the first side of the rack.

2. The rekeyable lock cylinder of claim 1, wherein when the locking bar is in the locked position, a portion of the flange of the locking bar projects past the plane of the first side of the rack and is disposed within the second engaging groove.

3. The rekeyable lock cylinder of claim 2, wherein the locked position is a first locked position, the locking bar movable to at least a second locked position engaged with the first engaging groove of the cylinder body and the flange is completely removed from the second engaging groove of the rack for blocking rotation of the plug assembly, wherein the first locked position is a consecutive key cut position relative to the unlocked position and the second locked position is a non-consecutive key cut position relative to the unlocked position.

4. The rekeyable lock cylinder of claim 1, wherein each of the plurality of racks include a plurality of key following engaging features on an opposite second side of the plurality of racks and spaced apart at a key cut distance, and wherein the opening distance greater than twice the key cut distance.

5. The rekeyable lock cylinder of claim 1, wherein each of the plurality of racks include a plurality of key following engaging features on an opposite second side of the plurality of racks and spaced apart at a key cut distance, and wherein half of the opening distance is greater than the key cut distance.

6. The rekeyable lock cylinder of claim 1, wherein the second engaging groove has a recessed distance that is orthogonal to the opening distance and the flange has an extension distance that is orthogonal to the thickness distance of the locking bar, and wherein the recessed distance of the second engaging groove is greater than the extension distance of the flange.

7. The rekeyable lock cylinder of claim 1, wherein the locking bar has a first end and an opposite second end extending along the longitudinal axis, the blocking portion includes a first recessed area proximate the first end for receiving the one or more biasing members and a second recessed area proximate the second end for receiving the one or more biasing members, wherein the blocking portion is disposed on both longitudinal sides of the first and second recessed areas.

8. The rekeyable lock cylinder of claim 7, wherein the one or more biasing members are retained within the carrier via one or more clips, the one or more clips having a receiving portion for securing the one or more biasing members, the one or more biasing members disposed between the receiving portion and the locking bar.

9. The rekeyable lock cylinder of claim 1, wherein the blocking portion of the locking bar is squared-off with 90° corners and the first engaging groove of the cylinder body has a corresponding shape.

10. The rekeyable lock cylinder of claim 1, wherein the carrier defines a longitudinal slot that slidably receives the locking bar, and wherein when the locking bar is in the locked position, torque applied to the plug assembly is isolated from the plurality of racks.

11. A rekeyable lock cylinder comprising:
a cylinder body extending along a longitudinal axis, the cylinder body defining an interior surface having a first engaging groove extending along the longitudinal axis, wherein the first engaging groove has a pair of square interior corners such that a first groove surface and a second groove surface face each other and are parallel; and

- a plug assembly at least partially disposed within the cylinder body and selectively rotatable around the longitudinal axis, the plug assembly comprising:
- a plug body;
  - a plurality of key followers slidably mounted on the plug body; and
  - a carrier subassembly supported on the plug body, the carrier subassembly comprising:
    - a carrier slidably supported on the plug body;
    - a plurality of racks slidably mounted on the carrier, each of the plurality of racks engaged with a corresponding key follower of the plurality of key followers, wherein the plurality of racks are selectively disengageable from the plurality of key followers via movement of the carrier to facilitate rekeying of the lock cylinder, each of the plurality of racks having a second engaging groove recessed within a first side of the rack; and
    - a locking bar supported on the carrier and having a blocking portion configured to be received at least partially within the first engaging groove of the cylinder body and an opposite flange configured to be received at least partially within the second engaging groove of the plurality of racks, the locking bar movable between at least a locked position engaged with the first engaging groove of the cylinder body for blocking rotation of the plug assembly, and an unlocked position disengaged from the first engaging groove of the cylinder body allowing rotation of the plug assembly, the locking bar biased towards the plurality of racks with one or more biasing members, wherein the locking bar includes a first bar surface and a second bar surface, the first and second bar surfaces parallel to each other and extending between the blocking portion and the flange, wherein the blocking portion has a pair of square exterior corners that correspond to the square interior corners of the first engaging groove, and wherein when the locking bar is in the locked position, the first and second groove surfaces and the first and second bar surfaces are all in parallel such that torque applied to the plug assembly is prevented from being translated from the locking bar to the plurality of racks.
12. The rekeyable lock cylinder of claim 11, wherein the locking bar has a first end and an opposite second end extending along the longitudinal axis, the blocking portion includes a first recessed area proximate the first end for receiving the one or more biasing members and a second recessed area proximate the second end for receiving the one or more biasing members, wherein the blocking portion is disposed on both longitudinal sides of the first and second recessed areas.

13. The rekeyable lock cylinder of claim 12, wherein the one or more biasing members are retained within the carrier via one or more clips, the one or more clips having a receiving portion for securing the one or more biasing members, the one or more biasing members disposed between the receiving portion and the locking bar.
14. The rekeyable lock cylinder of claim 13, wherein the carrier includes a curved surface and a flat surface, the one or more clips extend entirely around an outer perimeter of the curved surface.
15. The rekeyable lock cylinder of claim 11, wherein the second engaging groove has an opening distance at the first side, and the locking bar has a thickness distance between the first and second bar surfaces that is less than the opening distance of the second engaging groove, and wherein when the locking bar is in the unlocked position, the flange is fully received within the second engaging groove such that gaps are formed between the first side of the rack and the first and second bar surfaces of the locking bar along a plane defined by the first side of the rack.
16. The rekeyable lock cylinder of claim 15, wherein each of the plurality of racks include a plurality of key following engaging features on an opposite second side of the plurality of racks and spaced apart at a key cut distance, and wherein the opening distance greater than twice the key cut distance.
17. The rekeyable lock cylinder of claim 15, wherein each of the plurality of racks include a plurality of key following engaging features on an opposite second side of the plurality of racks and spaced apart at a key cut distance, and wherein half of the opening distance is greater than the key cut distance.
18. The rekeyable lock cylinder of claim 15, wherein the second engaging groove has a recessed distance that is orthogonal to the opening distance and the flange has an extension distance that is orthogonal to the thickness distance of the locking bar, and wherein the recessed distance of the second engaging groove is greater than the extension distance of the flange.
19. The rekeyable lock cylinder of claim 11, wherein when the locking bar is in the locked position, a portion of the flange of the locking bar projects past a plane of the first side of the rack and is disposed within the second engaging groove.
20. The rekeyable lock cylinder of claim 19, wherein the locked position is a first locked position, the locking bar movable to at least a second locked position engaged with the first engaging groove of the cylinder body and the flange is completely removed from the second engaging groove of the rack for blocking rotation of the plug assembly, wherein the first locked position is a consecutive key cut position relative to the unlocked position and the second locked position is a non-consecutive key cut position relative to the unlocked position.
